DEVICE FOR CARRYING LUGGAGE AND
OTHER ARTICLES

Albert Schulein, New York, N. Y.

Application November 24, 1945, Serial No. 630,642

10 Claims. (Cl. 280—36)

1

This invention relates to new and useful improvements in devices for carrying luggage and other articles.

More specifically, the invention proposes a new and improved device for carting luggage, shopping bags, and other articles, which is adjustable to accommodate articles of different sizes.

The invention contemplates characterizing the new and improved adjustable moving device for luggage, and the like, by the fact that it includes a plate-like undercarriage for resting on and being moved along the ground. It is proposed that the undercarriage be supported on casters or wheels. A back is hingedly mounted on the undercarriage for folding flat against said undercarriage and for assuming an erect position when desired. It is proposed to associate a sectional rectangularly shaped frame having extendable and retractable sections, with the top portion of said back, upon which luggage of different sizes may be conveniently supported. It is also proposed to provide an extendable and retractable brace adjustably mounted upon said undercarriage for supporting said frame in a raised position.

It is proposed to provide said back with an extendable handle by which the device may be conveniently moved around.

A modified form of the new and improved adjustable moving device is proposed in which a pair of foldable side arms is arranged upon the sides of the back for carrying a market bag, or other bag, or objects.

Another object of the invention is the construction of a device as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Figure 1 is a perspective view of an adjustable device for luggage, and the like, illustrated in an open position.

Figure 2 is a back view of Figure 1.

Figure 3 is a fragmentary enlarged vertical sectional view taken on the line 3—3 of Figure 2.

Figure 4 is a fragmentary enlarged vertical sectional view taken on the line 4—4 of Figure 2.

Figure 5 is a horizontal sectional view taken on the line 5—5 of Figure 1.

2

Figure 6 is a fragmentary enlarged sectional view taken on the line 6—6 of Figure 1.

Figure 7 is a fragmentary sectional view taken on the line 7—7 of Figure 3.

Figure 8 is a perspective view of another adjustable moving device for luggage and other articles, embodying a modified form of this invention.

Figure 9 is a fragmentary enlarged detailed side elevational view of a portion of Figure 8.

Figure 10 is a side elevational view of the device shown in Figure 8 drawn on an enlarged scale and illustrated in a folded condition.

The new and improved adjustable moving device for luggage and other articles, in accordance with this invention, includes a plate-like undercarriage 12 for resting on and being moved along the ground. The undercarriage is provided with casters 13, or wheels by which it may be conveniently moved.

A back 14 is hingedly mounted on the undercarriage 12 and is capable of being folded down flat against the top face of the undercarriage 12. The back 14 may also be extended upwardly so as to assume an erect position upon the back end of the undercarriage 12. It is illustrated in this latter condition, upon the drawing. Hinges 16 connect the back 14 with the undercarriage 12 so that it may be folded down, or moved to its erect position.

A clamp bolt 18 is pivotally supporting on the bottom leaf of the hinge 16 and is extendable through a slot 19 formed in the top leaf of the hinge 16. The bolt 18 is provided with a wing nut 20 by which the leaves of the hinge 16 may

be locked together so as to lock the back 14 in its upright position. A handle 21 is mounted on and extendable from the back 14. This handle 21 is in the nature of an inverted U-shaped member. The arms of this inverted U-shaped member

slidably engage through passages 23 formed through the back 14. The inner ends of the arms of the handle 21 have enlarged heads 24 which prevent them from being completely drawn out from the openings 23. Each of the arms of the handle 21 is associated with a latch 25 by which the handle 21 may be latched in an extended position. Each latch 25 includes a bolt 26 which is urged inwards by an expansion spring 27. The inner end of the bolt 26 is engageable with an opening 28 formed in the handle 21. Each bolt 26 has a head 29 by which it may be manually moved.

A sectional rectangularly shaped frame 30 composed of four telescopically inter-engaged L-shaped sections 31, 32, 33 and 34, is hingedly

50 55

mounted on the top portion of the back 14. More particularly, the sections 33 and 34 have one of their arms engaging into a horizontal passage 36 formed in the back 14. The inner ends of these arms are formed with heads 37 and 38 which prevent their complete disengagement from the ends of the passage 36. It is possible to force the sections of the frame 30 together, or move them apart so as to decrease or increase the size of the frame. In this way the frame 30 may be adjusted for luggage of different sizes. The upper surface of the sections 33 and 34 may be provided with spaced grooves to facilitate placing of a shopping bag thereon if desired.

An extendable and retractable brace 40 is adjustably mounted on the undercarriage 12 and is for the purpose of supporting the frame 30 in a raised position. This brace 40 is composed of telescoping sections 41 and 42. The section 41 has a top forked end 43 the fingers of which are provided with clamps 44 and 45 adapted to respectively clamp the adjacent arms of the sections 31 and 32. The telescopic sections 41 and 42 may be locked in extended, or retracted positions by a clamp screw 46 which threadedly engages one of the sections and abuts the other of the sections. The section 42 is pivotally supported by a pintle 47 upon a slide 48 which is slidably mounted in a groove 49 formed in the top face of the undercarriage 12. The slide 48 is provided for the clamp screw 50 which may be screwed down to lock the slide 48 in selected positions along the length of the groove 49. The back end of the groove 49 has an enlarged portion 51 into which the top forked end 43 of the section 41 may engage. The groove 49 and slide 48 are of dovetailed shapes (see Fig. 7). Handles 53 are mounted on the sides of the back 14.

The operation and use of the adjustable moving device for luggage may be understood from the following:

In Fig. 1 it is illustrated in an open position ready to be used. A piece of luggage may be placed on the frame 30. Other articles may be placed on the top face of the undercarriage 12. The moving device may then be pushed along the ground. It eliminates the necessity of carrying the luggage and other articles.

The moving device may be easily folded when it is not being used. It may then be conveniently carried in a piece of luggage, or stored away. The device may be folded by first forcing the clamps 44 and 45 from the adjacent arms of the sections 31 and 32. Then, the brace 40 may be folded down into the groove 49. The handle 21 is freed by opening the latches 25 and then is pushed down into the back 14. The back 14 is now freed by opening the clamp bolt 18 and nut 20 and then the back 14 is folded down upon the top of the undercarriage 12. The frame 30 is swung around to be located upon the top face of the folded down back 14. The frame 30 is collapsed by moving the various sections together.

In Figs. 8-10, a modified form of the invention has been disclosed which is very similar to the prior form, distinguishing merely in the fact that foldable side arms 55 are mounted on the sides of the back 14. Each of these foldable side arms 55 includes a main arm 56 which is pivotally supported by a pintle 57 at its back end on the side of the back 14. The foldable side arms also include brace arms 58 which are pivotally supported at their back ends by pintles 59 on to the sides of the back 14. The front ends of the

brace arms 58 are provided with pins 60 which engage slots 61 formed in the main arms 56. The slots 61 have recesses 62 into which the pins 60 may engage for locking the main arms 56 in horizontal positions. A shopping bag, or other bag, may be supported across the side arms 55.

In other respects this form of the invention is similar to that previously shown and like reference numerals identify like parts in each of the several views.

The adjustable moving device for luggage may be folded in substantially the same way as described relative to the prior form. The foldable arms 55 are folded against the sides of the back 14. Figure 10 illustrates the device in its folded condition.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. An adjustable moving device for luggage and the like, comprising a plate-like undercarriage for resting on and being moved along the ground, a back hingedly mounted on said undercarriage for folding flat against said undercarriage and for assuming an erect position upon the back end of said undercarriage, a sectional rectangularly shaped frame having extendable and retractable sections and hingedly mounted upon the top portion of said back, and an extendable and retractable brace adjustably mounted upon said undercarriage for supporting said frame in a raised position.

2. An adjustable moving device for luggage and the like, comprising a plate-like undercarriage for resting on and being moved along the ground, a back hingedly mounted on said undercarriage for folding flat against said undercarriage and for assuming an erect position upon the back end of said undercarriage, a sectional rectangularly shaped frame having extendable and retractable sections and hingedly mounted upon the top portion of said back, and extendable and retractable brace adjustably mounted upon said undercarriage for supporting said frame in a raised position and a handle mounted on said back.

3. An adjustable moving device for luggage and the like, comprising a plate-like undercarriage for resting on and being moved along the ground, a back hingedly mounted on said undercarriage for folding flat against said undercarriage and for assuming an erect position upon the back end of said undercarriage, a sectional rectangularly shaped frame having extendable and retractable sections and hingedly mounted upon the top portion of said back, an extendable and retractable brace adjustably mounted upon said undercarriage for supporting said frame in a raised position and an inverted U-shaped handle mounted on said back and having its side arms engaging into openings extended downwards from the top edge of said back.

4. An adjustable moving device for luggage and the like, comprising a plate-like undercarriage for resting on and being moved along the ground, a back hingedly mounted on said undercarriage for folding flat against said undercarriage and for assuming an erect position upon the back end of said undercarriage, a sectional rectangular

larly shaped frame having extendable and retractable sections and hingedly mounted upon the top portion of said back, and an extendable and retractable brace adjustably mounted upon said undercarriage for supporting said frame in a raised position and an inverted U-shaped handle mounted on said back and having its side arms engaging into openings extended downwards from the top edge of said back, said side arms being provided with heads for preventing them from coming out from said passage.

5. An adjustable moving device for luggage and the like, comprising a plate-like undercarriage for resting on and being moved along the ground, a back hingedly mounted on said undercarriage for folding flat against said undercarriage and for assuming an erect position upon the back end of said undercarriage, a sectional rectangularly shaped frame having extendable and retractable sections and hingedly mounted upon the top portion of said back, and an extendable and retractable brace adjustably mounted upon said undercarriage for supporting said frame in a raised position, said frame having four angle shaped sections telescopically engaged with each other.

6. An adjustable moving device for luggage and the like, comprising a plate-like undercarriage for resting on and being moved along the ground, a back hingedly mounted on said undercarriage for folding flat against said undercarriage and for assuming an erect position upon the back end of said undercarriage, a sectional rectangularly shaped frame having extendable and retractable sections and hingedly mounted upon the top portion of said back, and an extendable and retractable brace adjustably mounted upon said undercarriage for supporting said frame in a raised position, said frame having four angle shaped sections telescopically engaged with each other, said frame being hingedly mounted at one of its sides upon said back.

7. An adjustable moving device for luggage and the like, comprising a plate-like undercarriage for resting on and being moved along the ground, a back hingedly mounted on said undercarriage for folding flat against said undercarriage and for assuming an erect position upon the back end of said undercarriage, a sectional rectangularly shaped frame having extendable and retractable sections and hingedly mounted upon the top portion of said back, an extendable and retractable brace adjustably mounted upon said undercarriage for supporting said frame in a raised position and means for latching said back in its erect position.

8. An adjustable moving device for luggage and the like, comprising a plate-like undercarriage for resting on and being moved along the ground, a back hingedly mounted on said undercarriage for folding flat against said undercarriage and for assuming an erect position upon the back end of said undercarriage, a sectional rectangularly shaped frame having extendable and retractable sections and hingedly mounted upon the top portion of said back, an extendable and retractable brace adjustably mounted upon said undercarriage for supporting said frame in a raised position, and means for locking said brace in various positions on said undercarriage.

9. An adjustable moving device for luggage and the like, comprising a plate-like undercarriage for resting on and being moved along the ground, a back hingedly mounted on said undercarriage for folding flat against said undercarriage and for assuming an erect position upon the back end of said undercarriage, a sectional rectangularly shaped frame having extendable and retractable sections and hingedly mounted upon the top portion of said back, and an extendable and retractable brace adjustably mounted upon said undercarriage for supporting said frame in a raised position, said brace being pivotally connected with a slide engaging a groove formed in the top face of said undercarriage.

10. An adjustable moving device for luggage and the like, comprising a plate-like undercarriage for resting on and being moved along the ground, a back hingedly mounted on said undercarriage, for folding flat against said undercarriage and for assuming an erect position upon the back end of said undercarriage, a sectional rectangularly shaped frame having extendable and retractable sections and hingedly mounted upon the top portion of said back, an extendable and retractable brace adjustably mounted upon said undercarriage for supporting said frame in a raised position, and a pair of foldable side arms mounted on the sides of said back.
